PICKER CONTROL FOR LABEL-APPLYING
MACHINES

Sidney T. Carter, Worcester, Mass., assignor to
Economic Machinery Company, Worcester,
Mass., a corporation of Massachusetts

Application January 25, 1949, Serial No. 72,641

24 Claims. (Cl. 216—54)

1

This invention pertains to label-applying machines, more especially to an improved control mechanism designed to prevent withdrawal of labels from the supply or the application of adhesive to the surface of a transfer pad whenever for any reason there is no article to be labeled in the label-receiving position at the proper time in the cycle of operations. The invention is herein illustrated by way of example in its application to a machine of the kind disclosed in the patent to Ekvall No. 1,630,235, dated May 24, 1927, but modified as to the pickers and related parts as shown in the patent to Carter No. 2,414,019, dated January 7, 1947.

The Ekvall machine is the kind commonly known as a "straight-away" machine, the articles to be labeled being progressed step-by-step along a substantially rectilinear path, stopping at the label-receiving position to receive a label and then continuing on in the same direction. The machine of the Ekvall patent illustrates the use of spaced, swinging picker elements which receive a coating of gum from a gum-applying roll, then advance to a magazine where a label adheres to the gummed surface of the pickers and then retract to a transfer position adjacent to the article to be labeled where they dwell while a transfer pad enters between the picker elements and carries the label from the picker elements to the article to be labeled. In the patented machine the shaft which carries the pickers is rocked back and forth by means including a knuckle joint whose parts are normally in a substantially straight line. When the parts of the knuckle joint are so positioned, the picker is swung through a predetermined arc and at one limit of its motion contacts the labels in the magazine. However, in the absence of an article at the labeling position, a feeler device, responsive to the presence or absence of an article to be labeled, actuates means operative to break the knuckle joint, with the result of shortening the arc of movement of the picker shaft sufficiently to prevent the picker from reaching the magazine. Thus, delivery of labels from the magazine is prevented except when an article is properly positioned to receive a label.

In the patent to Carter the picker elements are shown as being laterally separable and a pneumatic transfer pad is employed. When the picker elements (then disposed edge-to-edge) arrive at the transfer position carrying a label adherent to their gummed surfaces, the picker elements slide away from each other to right and left while the pneumatic transfer pad by

2

suction grips the label. The transfer pad then advances between the separated picker elements to place the label on the article. In this Carter arrangement, although means were employed, as in Ekvall, to prevent the picker from taking a label from the magazine (in the event that there is no article at the label-receiving position), the gum-coated picker if it should return empty to the transfer point would apply gum to the surface of the pneumatic transfer pad. The adhesive coating thus applied to the transfer pad would cause the next label delivered adhesively to cling to the transfer pad, thus preventing the proper operation of the machine. On the other hand, if the picker stroke were so shortened that it would not receive its usual coating of gum, the picker might approach the magazine, on its next normal stroke, without adhesive and would thus fail to deliver a label to the transfer pad.

The principal object of the present invention is to provide control means which not only prevents the picker (although it receives its usual coating of adhesive) from taking labels from the magazine, but also prevents the application of adhesive to the pneumatic transfer pad in the event that no article is present at the label-receiving position at the proper time in the cycle of operations. A further object is to provide control means employing substantially the same basic mechanism as that disclosed in the Ekvall patent but modified for use in a machine employing the Carter type of picker. A further object is to provide a very simple modification of the control mechanism of the Ekvall patent whereby the desired result is accomplished. A further object is to provide improved picker and transfer means for use in a label-applying machine, whether of the straight-away type like that of Ekvall, or of other type, for example, the so-called "semi-automatic" machine, in which the articles to be labeled are fed by hand, whereby the improvident application of gum to a transfer element is prevented.

In machines which employ a pneumatic transfer pad it has been customary to provide an air pump of conventional type having a cylinder and reciprocating piston. Such pumps are expensive; they occupy considerable space; they often require the provision of a gear drive and they necessitate the use of properly actuated valves to determine the times at which suction shall be created and relieved. In the machine of the Carter patent above referred to, there is a vertical rock shaft which actuates the device for

separating the picker elements at the transfer point and this rock shaft is accurately timed with reference to the motion of the transfer pad. A further object of the present invention is to take advantage of the presence of this oscillatory shaft by employing it for actuating a very simple suction-creating device which (without valves and without requiring intervening gearing) derives its motion directly from this oscillatory shaft and creates and releases the suction at the proper times in the cycle.

A further object is to provide suction-creating means employing metallic bellows as the expanding and contracting element.

Since the articles to which labels are to be applied do not always have exactly vertical side walls, a flat transfer pad having its label-contacting surface always in a vertical plane may fail to apply such uniform pressure to the label as to insure its adhesion at all points to the article. A further object of the present invention is to provide an improved support for a pneumatic transfer pad such as to insure uniform adhesion of the label regardless of any slight inclination of the side wall of the article to which the label is to be applied. Other and further objects and advantages of the invention will be pointed out in the following more detailed description and by reference to the accompanying drawings wherein:

Fig. 1 is a fragmentary rear elevation (certain parts being omitted) of a label-applying machine of the straight-away type, embodying the present invention;

Fig. 2 is a fragmentary vertical section, to larger scale, on the line 2-2 of Fig. 1;

Fig. 3 is a diagrammatic, fragmentary, transverse section substantially on the line 3-3 of Fig. 1;

Fig. 4 is a fragmentary front elevation showing the means for supporting the two picker elements and for moving them toward and from each other;

Figs. 5, 6, 7 and 8 are fragmentary, diagrammatic front elevations, to small scale, illustrating the cycle of relative movement of the two picker elements;

Fig. 9 is a fragmentary side elevation, partly in vertical section illustrating the picker-stroke control means of the present invention, the parts being shown in the position which they normally occupy when an article is about to be delivered to the label-receiving position and with the picker at the limit of its normal picking stroke;

Fig. 10 is a fragmentary view similar to Fig. 9 but showing the parts of the control mechanism in the relative positions which they occupy at the end of the normal labeling-delivery stroke of the picker;

Fig. 11 is a fragmentary section on the line 11-11 of Fig. 10;

Fig. 12 is a fragmentary side elevation generally similar to Fig. 9 but showing the picker at the limit of its abnormal or shortened picking stroke when no article is in position to receive a label;

Fig. 13 is a view similar to Fig. 10 but showing the picker at the limit of its abnormal or augmented delivery stroke when no article is in position to receive a label;

Fig. 14 is a fragmentary front elevation, to larger scale, of the pneumatic transfer pad and associated parts;

Fig. 15 is a side elevation of the parts shown in Fig. 14 and illustrating the means for tilting the

pad to conform to the slope of the surface to which the label is to be applied; and

Fig. 16 is a fragmentary plan view, to larger scale than Fig. 3, showing details of the bellows-type pump desirably employed in the practice of the present invention.

Reference may be had to the above patents to Ekvall and Carter, and to the patent to Holm No. 1,901,101, dated March 14, 1933 (referred to in the Carter patent), for structural details, not herein specifically described.

Referring to the drawings (Figs. 1 and 2), the numeral 1 designates a table or bed constituting a support for the label-attaching appliances of the present invention, this bed being supported in any suitable way, for example by legs (not shown), at a desirable elevation above the floor. Below this bed and supported in appropriate bearings (not here shown) is the power-driven cam shaft 2 which is driven at a substantially constant speed by an individual motor or other source of energy.

Upright frame members 3 are secured at their lower ends to the bed or table 1. The machine herein illustrated, by way of example, is a straight-away machine of the kind illustrated in the Ekvall patent and has a rectilinear guideway, here shown as comprising parallel spaced rails 4 upon which the articles to be labeled are supported and along which they are propelled step-by-step in the performance of the operation. As illustrated in Figs. 1 and 2, the mechanism is shown as operating upon square-shaped bottles A having paneled faces to receive the labels, but it is to be understood that the mechanism is equally well adapted for labeling flat, oval or other shaped bottles, containers or packages and when the terms "bottle" or "article" are herein employed, such terms are intended to include all such containers and articles for the labeling of which the mechanism here disclosed is applicable.

As shown in Fig. 2, retaining rails 5 are arranged above and parallel with and to the rear of the rails 4 for engagement with the rear side of the articles A as the latter pass through the label-applying station. Beneath the rails 4 there is arranged suitable mechanism for advancing the articles intermittently along the guideway, such mechanism for example, being of the kind more fully described in the patent to Ekvall, above referred to, and including, among other elements, parts 7 (Fig. 2) which engage the sides of the articles to push or propel them intermittently along the guideway.

The label magazine 8 may be of conventional type having means for supporting a stack of labels L in such a way that the bottom label may readily be withdrawn from the stack by the picker.

At the upper forward part of the machine there is arranged a transverse shaft 9, Fig. 2, supported in bearings in the frame members 3 and having fixed to it the upper end of a lever 10 which has a gum-transfer roll 11 journaled at its lower end. The shaft 9 also has a crank arm 12 fixed to it. The upper end of a connecting rod 13 is pivotally connected to the forward end of the crank arm 12 and extends down to a point below the table 1 where it is pivotally secured to the forward end of a lever 14 whose rear end is fulcrumed on a shaft 15 mounted in a bracket 16 secured to the underside of the table 1. The lever arm 14 is provided with a cam roll at an intermediate point which engages a cam 17 fixed to the shaft 2,

the cam being of such peripheral contour as to swing the arm 10 and thus move the gumming roll 11 at the proper times and in proper sequence to cooperate with the other elements of the machine in the labeling operation.

Supported on the forward part of the table 1 (Fig. 2) is a reservoir 18 for gum or other suitable adhesive and a rotating roll 19 is journaled in suitable bearings, carried by the gum receptacle, and so positioned that as the gum-transfer roll 11 is swung forwardly its surface contacts the peripheral surface of the rotating roll 19 and thus is coated with gum.

At the upper rear portion of the machine there is arranged a transverse shaft 20 which supports the picker device. This picker device is here illustrated, by way of example, as of the kind disclosed in the Carter patent above referred to. Thus, the shaft 20 carries a pair of sleeves 21 and 22 which are free to slide axially of the shaft but which are so connected to the shaft that they turn with it. These sleeves are provided with brackets 23 and 24, respectively, to which the upper ends of the picker blades 25 and 26 are secured. These blades are of generally conventional type such as used in machines in which the picking of the labels is accomplished by means of gum-coated pickers and have the slots 27 and 28 to accommodate the label-retaining hooks of the label magazine.

A vertical, oscillatory shaft 29 is arranged at the left-hand side of the machine, as viewed in Figs. 1 and 4, this shaft corresponding in function to the oscillatory vertical shaft shown at the right-hand side of Fig. 9 of the Carter patent. At its upper end this shaft is provided with an elongate plate 30 to whose opposite ends connecting rods 31 (one only being shown) are pivotally connected, the opposite ends of the respective rods being secured to sleeves 32 and 32^a which are arranged to slide on a shaft 32^a parallel to shaft 20. By means of this oscillatory shaft 29 and the connections which are described more in detail in the Carter patent, the picker elements 25 and 26 are moved toward and away from each other so as at various times in the operation to occupy the relative positions shown in Figs. 5 to 8, respectively. The shaft 29 extends down through an opening in the table 1 and is provided at its lower end with a crank arm having a pin which engages a cam groove in the periphery of a cam 33 (Fig. 1) on shaft 2.

A shaft 34, Figs. 1 and 2, is arranged transversely of the machine just above the table 1 and below the guideway for the articles. This shaft has a crank arm 35 secured to it. The forward end of this crank arm is pivotally connected to the connecting rod 36 which passes down through an opening in the table 1 and whose lower end is connected to the forward end of a lever 37 which is fulcrumed at its rear end on the shaft 15. This lever has a roll 38 which engages the periphery of a cam 39 fixed to the shaft 2.

A second arm 40 (Fig. 2) is secured to the arm 34 and constitutes a support for the label transfer pad. Referring more particularly to Figs. 14 and 15, the arm 40 is provided near its upper end with a boss 41 in which is secured a stub shaft 42 on which turn ears projecting from the rear face of a pad-carrying plate 43. A coiled compression spring 44 bears, at its opposite ends, against the upper part of the arm 40 and the upper portion of the pad-carrying plate, respectively, thus tending to swing the upper part

of the pad-carrying plate clockwise (Fig. 15), that is to say, toward the article guide. An adjustable stop screw 45, having threaded engagement with an opening in the arm 40, is arranged to limit such swinging movement of the pad carrier. The pad carrier is provided with an upwardly extending rigid arm 46, provided at its upper end with the adjustable stop screw 47 which, at times in the cycle of operations, engages a fixed abutment 48 secured at its upper end to a fixed member 49 of the machine frame.

The transfer pad 50 is here illustrated as of the pneumatic or suction type. Its internal construction may be conventional, its label-contacting face being provided with a multitude of suction orifices (see Fig. 7), all of which communicate with an interior chamber or chambers from which one or more flexible suction conduits 51 lead to a manifold, mounted on the arm 40, from which a single flexible suction conduit 52 leads to the pump or other suction-creating device. As here illustrated, Figs. 3 and 16, the opposite end of the conduit 52 is secured to a rigid tube 53 which is fixed in an opening in one of the frame members 3. This tube has an extension 54 which is rigidly secured to one head 55 of a metallic bellows 56 of conventional type. The movable head 57 of this bellows is connected by a rod 58 to a crank pin 59 secured to a crank arm 60 fixed to the lower part of the oscillatory shaft 29, which, as above described, controls the opening and closing movement of the picker elements. As the shaft 29 oscillates, the bellows device 56 is expanded and contracted in accurately timed relation to the operation of the pickers, thus creating alternate suction and pressure at the orifices in the suction pad.

Referring to Figs. 1 and 3, the machine is provided with a feeler lever 61 mounted upon a vertical shaft 62 so as to swing in a horizontal plane. This lever 61 carries the feeler member 63 which is so disposed relatively to the guideway along which the articles move that it is contacted by such articles as they move toward the labeling position, as indicated by the article A' (Fig. 3). A spring 64 tends to swing the lever 61 in such a direction as to move the feeler member 63 across the article path, but when an article, as shown at A', Fig. 3, is moving along the path according to the normal sequence of operations, the contact of such article with the feeler 63 swings the feeler lever 61 in a clockwise direction, as viewed in Fig. 3, so that the opposite arm or tail 65 of the lever is moved forwardly in opposition to the spring 64.

The location of the feeler is such, relative to the rate of advance of articles along the guideway and to the cycle of operations of the machine, that if an article A' is in the detecting position at the commencement of the cycle which will result in the application of a label to that particular article when said article arrives at the label-applying station (just to the rear of the transfer pad), then such cycle will be a normal cycle; if at the commencement of said cycle there is no article A' at the detecting position, then the cycle will be an abnormal cycle during which no label is taken from the magazine.

Two crank arms 66 and 67 (Figs. 10-13) are mounted on the picker-supporting shaft 20. The arm 66 is fixed to this shaft, while the arm 67 may rotate relatively to the shaft. These arms 78 have normally abutting parts which are nor-

normally maintained in contact with each other by a strong spring S. However, the arms 66 and 67 may move relatively to each other, as permitted by extension of the spring S, so as to prevent a smash if the picker should encounter an obstacle during its rearward travel.

A picker-actuating rod 68 extends down through an opening in the table 1 and is connected at its lower end to a lever 69 (Fig. 3) fulcrumed on the shaft 15 and having a cam follower roll 70 which engages the picker-oscillating cam 71. The upper end of the rod 68 is provided with an elongate head H to which the lower end of a part K is pivotally connected, the upper end of this part K being pivoted on a crank pin 71 projecting from the forward end of the crank arm 67. The parts H and K constitute the elements of a knuckle joint for transmitting motion from the rod 68 to the crank arm 67, as hereafter more fully described.

The part K has a rigid arm 72, and an abutment surface 73 which normally engages the upper end of the head H and prevents the knuckle joint from breaking in the wrong direction. The arm 72 is connected by a spring 75 to a bracket 76 projecting from the head H. This spring 75 normally holds the parts K and H in vertical axial alignment, and tends to restore the knuckle joint to normal condition when it has been broken. The part K also has an arm 72^a to which is pivotally connected the upper end of a depending rod 77 provided with a hook 78 at its lower end.

A stub shaft 79 is secured to one of the frame members 3 and constitutes a pivot for a control member 80. A friction washer 81 (Fig. 11) bears against the outer surface of the control member and is pressed against the latter by a compression spring 82. This arrangement permits the control member 80 to be swung about the pivot pin 79 but retains the control member temporarily in any position in which it may be swung. Preferably the control member has a handle 84 projecting above its pivot by means of which it may be moved manually, if desired. This control member 80 has a hook 85 at its lower end and above the hook the control member is shaped to provide the cam surfaces 86, 87 and 88 (Fig. 10), the latter forming one wall of an open recess or slot 90. The arm 72 of the part K, above described, is provided with a pin 74 on which is mounted a roller 91, which at times cooperates with the hook 85 and at other times with the cam surfaces of the control member 80.

The operation of the mechanism is substantially as follows assuming that the parts H and K are in vertical alignment, as shown in Fig. 9, this being the normal position of the parts when articles are being fed in proper succession along the guideway. Assuming that articles are moving along the guideway in orderly succession and that an article A', in approaching the labeling station, has reached the detecting position (Fig. 3), this article engages the feeler or detector 63 and thus holds the latter in the position indicated in Fig. 3 so that the tail portion 65 of the lever 61 is located relatively to the hook 78, as shown in Fig. 9. The rod 29 is oscillating back and forth once during each cycle of the machine operations and the rods 13, 36 and 68 are moving up and down once for each cycle. Normally, an article arrives at the detecting position, as indicated at A' (Fig. 3), just at the completion of the previous label-applying cycle, the transfer pad being at the extreme rearward limit of

its movement. While the label was being transferred from the magazine to the article, during the previous cycle, the lever 10 has been moved forwardly to bring the transfer roll 11 into contact with the gum roll 19, and the arm has swung rearwardly. As the rod 68 starts upwardly to move the picker elements toward the magazine, the hook 78 moves idly up past the stop element 65, the knuckle joint elements K and H remain in normal alignment, the picker elements 25 and 26 are contacted by the now forwardly-swinging transfer roll 11 and receive a coating of adhesive (these elements at this time being relatively positioned as shown in Fig. 5) and the picker elements then continue on up toward the label magazine 8 until the gum-coated surfaces of the picker elements are brought into contact with the lowermost label L in the magazine. This lowermost label adheres to the gummed surfaces of the picker elements and the latter then swing downwardly away from the magazine, carrying this endmost label with them, as shown in Fig. 6. The pickers swing down to the transfer point where the surfaces of the pickers are substantially parallel with the surface of the article which is to receive the label. The pickers dwell at this point while the transfer pad 50 is swung upwardly until its label-contacting surface engages the ungummed face of the label. At this instant the oscillation of the shaft 29 causes the bellows device 56 to expand, thus creating suction at the suction orifices of the pad 50. At the same time, this oscillation of the shaft 29, acting through the connecting rods 31, causes the sleeves 32 to move away from each other along the shaft 32^a, thus slinging the picker elements 25 and 26 away from each other and relatively to the label L which is held by suction against the pad 50. This slinging action uniformly spreads the adhesive over the surface of the label. The pickers move apart until they occupy the relative positions shown in Fig. 7, whereupon the transfer pad enters between the pickers, carrying the label into contact with the surface of the article A which is to receive it. The pivotal mounting of the pad 50, on the carrying arm 49, permits the pad 50 to contact the label over its entire surface (when it first engages the label carried by the pickers) so as to insure good suction adhesion and then to rock, as may be necessary, to cause the label to engage the surface of the article to be labeled with uniform pressure. While the surface to be labeled may, in the majority of cases, be substantially vertical, it is not always exactly vertical, for example, as illustrated in Fig. 15 where the bottle A² is of a larger diameter at its shoulder portion than at its bottom so that the surface A³, which is to receive the label, slopes relatively to the vertical. In order to insure the proper contact of the label with such a sloping surface, the arm 46 is provided with the stop element 47. This stop element is adjusted to correspond to the slope of the surface S so that when the transfer pad approaches the label-applying position, this adjustable stop element 47 will contact the abutment 48, thus tipping the pad 50 to exactly the right inclination. Immediately after the label has been pressed against the article, the shaft 29 begins to oscillate in the opposite direction, thus compressing the bellows device 56 so as to cause pressure or at least to release the suction at the orifices 50, thus freely separating the pad 50 from the label. The labeled article now advances along the guideway and the

label-applying parts return to their initial position while another article is being fed into the label-receiving position.

The above represents the normal operation of the machine and during this operation the picker control mechanism occupies the relative positions shown in Figs. 9 and 10, the parts H and K being vertically aligned. When these parts are so vertically aligned, the upward movement of the rod 68 swings the arm 67 upward to a maximum extent and this arm, by contact with the arm 66, swings the picker shaft 20 and thus carries the pickers all of the way up to the label-picking position which is the normal limit of the arcuate path of the picker in this direction, as shown in Fig. 9. Upon the reverse or downward movement of the rod 68, the arm 67 is likewise swung downwardly and drags the arm 66 with it by means of spring S, the movement in this direction normally being such as to bring the pickers down to the transfer position (which is the normal limit of their motion in this direction) where they dwell during the transfer of the label to the pad 50 and while the pickers are separating to permit the pad to pass between them.

However, if, when the picker-actuating rod 68 begins to move up at the commencement of the next cycle of operations, there is no article in contact with the feeler 63 at the detecting position, the spring 64 will have swung the tail member 65 of the feeler lever 61 into the path of movement of the hook 78. Thus, as the rod 68 moves up, the hook 78 catches beneath the tail member 65 of the feeler lever and its upward movement is stopped. This causes the arm 72^a to swing downwardly, thus breaking the knuckle joint by throwing the part K out of alignment with the head H of the rod 68. At the same time, the arm 72 is swung up, as shown in Fig. 12, causing the stud roll 91 to engage the cam surface 88 so as to swing the control member 80 from the position shown in Fig. 10 to that shown in Fig. 12. Since the parts H and K are no longer in vertical alignment, the upward movement of the rod 68 does not swing the crank 67 upwardly quite so far as it does when the parts H and K are vertically aligned. Thus the turning of the shaft 20 in this direction by the rod 68 is through a lesser arc than normal and thus the picker 26 fails to reach the label-picking position and thus fails to contact and remove the lower label from the magazine. However, the picker elements 25 and 26 do move up far enough to receive a coating of adhesive from roll 11. The relative position of the picker and the magazine, under these abnormal conditions, is illustrated in Fig. 12.

Were the adhesively-coated picker to dwell at the normal transfer position in the usual way, the label-contacting surface of the transfer pad would come into contact with the adhesive coating on the picker and thus would become coated with adhesive which would interfere with the next transfer operation.

In accordance with the present invention, such a result is prevented by the action of the control device 80. This control device, as above pointed out, has been swung to the position of Fig. 12 through the operation of the detector device and intermediate parts. When in this position and when the rod 68 next starts to move downwardly, the spring 75 immediately restores the parts K and H to normal alignment, but the stud roll 91, carried by the arm 72, comes into contact with the hook 85 of the control device

as the rod 68 nears the lower end of its travel. When the stud roll 91 contacts the hook 85 during the downward movement of the rod 68, the arm 72 is swung in a counterclockwise direction (Fig. 13), thus again moving the parts K and H into the relative positions shown in Figs. 12 and 13. Thus, the connections between the picker-actuating cam and the shaft 20 are shortened and as the rod 68 moves to the same extent during every cycle, the crank arm 67 is moved downwardly through an abnormally large arc, thus swinging the picker shaft 20 to an extent such that the picker elements are moved beyond the normal transfer position, as illustrated in Fig. 13. Thus, when the pickers dwell, as occasioned by the contour of the picker cam, the transfer pad 50, which comes to rest at the normal transfer point (Fig. 13), is spaced from the adhesively-coated surfaces of the picker elements 25 and 26 so that the pad 50 does not receive a coating of adhesive.

The parts will continue to function in this abnormal way so long as there is no article delivered along the guideway to contact with the feeler 63. However, as soon as an article is properly fed along the guideway to contact the feeler 63, the latter is swung to the position shown in Fig. 3, thus removing the part 65 from the path of the hook 68 and the latter is then free to rise and fall in the normal way. As the rod 68 rises and the spring 75 moves the parts K and H into vertical alignment, the stud roll 91 moves upwardly and engages the cam surfaces 86 and 87 of the control member 80 and swings the latter in a clockwise direction, thus restoring the parts to the position shown in Fig. 9 where the stud roll 91 is located in the open slot 90 of the part 80. The machine now resumes its normal cycle of operations and continues to do so until the absence of an article causes the feeler or detector to initiate the abnormal cycle of operations again.

While one desirable embodiment of the invention has been herein illustrated by way of example, it is to be understood that the invention is broadly inclusive of all modifications falling within the scope of the appended claims. It is further to be understood that while the control mechanism has here been illustrated by way of example as embodied in a machine of the straight-away type, such control mechanism is equally applicable to machines of other type, for example the semi-automatic machine wherein the articles are fed by hand.

55 I claim:

1. In a labeling machine of the kind wherein a picker element is moved back and forth in an arcuate path during each cycle of operation of the machine and during each cycle receives adhesive from a supply, normally presses its adhesively-coated surface against the exposed label in a magazine, withdraws the label from the magazine and conveys it to a transfer point where it normally dwells during transfer of the label to another part, a picker, a picker-actuating cam designed to move the picker through a path of predetermined and constant arcuate length, the limits of said path normally being at the picking and transfer points, respectively, a detector 60 responsive to the absence of an article to be labeled at a detecting point, and means controlled by the detector, in the absence of an article at the detecting point, for shifting the limits of the path of the picker so that the picker fails 65 to reach the picking point while moving in one 70 75 to reach the picking point while moving in one

11

direction and passes beyond the transfer point when moving in the opposite direction.

2. In a labeling machine of the kind wherein an adhesively-coated picker element is moved back and forth in a predetermined path during each cycle of operation of the machine, normally presses its adhesively-coated surface against the exposed label in a magazine, withdraws the label from the magazine and conveys it to a transfer point where it normally dwells during transfer of the label to another part, a picker, a picker-actuating cam designed to move the picker through a path of predetermined and constant length, the limits of said path normally being at the picking and transfer points, respectively, a detector responsive to the absence of an article to be labeled at a detecting point, means controlled by the detector, in the absence of an article at the detecting point, for shifting the limits of the path of the picker so that the picker passes beyond the transfer point before it dwells, and means operative at every cycle of the machine to apply adhesive to the picker as the latter moves toward the picking position.

3. In a labeling machine of the kind wherein a picker element normally receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting connections between the cam and picker, said motion-transmitting means comprising a connection of variable length and means operative, at times, to change the length of said connection thereby to limit the travel of the picker toward the magazine sufficiently to prevent the picker from contacting a label in the magazine but without interfering with the application of adhesive to the picker, and means operative so to shorten said connection as to augment the movement of the picker in its movement away from the magazine, thereby to prevent the picker from dwelling at the normal transfer point.

4. In a labeling machine of the kind wherein a picker element normally receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting connections between the cam and picker, said motion-transmitting means including a knuckle joint, a detector which moves to a cycle-modifying position when it is not engaged by an article to be labeled, and control means, responsive to said position of the detector, operative to break the knuckle joint as the picker approaches the transfer point.

5. In a labeling machine of the kind wherein a picker element normally receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting

12

connections between the cam and picker, said motion-transmitting means including a knuckle joint having parts which are normally aligned, a detector which moves to an abnormal position when it is not engaged by an article to be labeled, a contact member carried by one element of the knuckle joint and which moves through a normal path as the picker oscillates, and a movable stop member whose position is controlled by the detector and which, when the detector assumes said abnormal position, engages said contact member and so changes the motion of the latter as to break the knuckle joint as the picker moves toward the transfer position.

15. 6. In a labeling machine of the kind wherein a picker element normally receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and means for transmitting motion from the cam to the picker, said motion-transmitting means including a knuckle joint comprising two pivotally connected elements which are normally kept in alignment by a spring but which are capable of relative movement to an abnormal angular position, one of said elements having a rigid arm provided with a stud, a pivotally supported hook device which is normally out of the path of said stud, and means operative to move the hook device into the path of the stud thereby to stop the latter and cause the elements of the knuckle joint to assume an abnormal angular position.

7. In a labeling machine of the kind wherein a picker element, at each cycle of operation, receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting connections between the cam and picker, said motion-transmitting means including a knuckle joint comprising two elements which are normally aligned but which are capable of relative movement to an abnormal angular position, a spring which tends to restore said elements to normal position, one of said elements having a rigid arm, and stop means engageable, at times, with said arm, as the picker moves toward transfer position, to cause said elements of the knuckle joint to assume an abnormal angular position.

8. In a labeling machine of the kind wherein a picker element normally receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting connections between the cam and picker, said motion-transmitting means including a knuckle joint comprising two pivotally connected elements which are normally kept in alignment by a spring, one of said elements receiving motion from the picker cam and the other of said elements being

Connected to the picker, said elements being capable of assuming an angular relation, means operative, at times, to cause said elements to assume such angular relation as the picker moves toward the magazine, and means responsive to such angular relation of the parts to cause said elements to assume said angular relation again as the picker next approaches the transfer point.

9. In a labeling machine of the kind wherein a picker element, at each cycle of operation, receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting connections between the cam and picker, said motion-transmitting means including a knuckle joint comprising two pivotally connected elements which are normally aligned, spring means for restoring said elements to alignment if they are moved out of alignment, said elements being capable of assuming an angular relation, means, including a detector operative in the absence of an article to be labeled, to cause said elements to assume such an angular relation as the picker moves toward the magazine, a rigid arm fixed to one of said elements, said arm having a stud near its end, a hook carrier having a hook which is normally out of the path of the stud, and means operative, at times, to move the hook carrier so that its hook is in the path of the stud, thereby to swing said arm and break the knuckle joint.

10. In a labeling machine of the kind wherein a picker element receives adhesive from a supply, normally presses its adhesive-coated surface against the exposed label in a magazine, withdraws the label from the magazine and conveys it and normally causes it to dwell at a transfer point, a movable picker, a picker-actuating cam designed to move the picker through a path of such extent as to permit it to perform its normal cycle of operations, and motion-transmitting connections between the cam and picker, said motion-transmitting means including a knuckle joint comprising two elements which are normally aligned, a spring normally keeping said elements in alignment but permitting them to assume an angular relation, means connecting one of said elements to the picker-oscillating shaft, a rigid arm fixed to said latter element, said arm having a stud near its end, and a pivoted hook carrier having a hook which is normally out of the path of said stud, said hook carrier having a cam element which, at times, is engageable by the stud as the picker moves toward the magazine, thereby to swing the hook carrier so as to dispose its hook in the path of the stud as the picker reverses its motion.

11. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the maga-

zine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, means controlled by the feeler in the absence of an article at the detecting position for so breaking the knuckle joint as the picker advances toward the magazine as to shorten the picker stroke in that direction sufficiently to prevent the picker from receiving a label, and means responsive to such breaking of the knuckle joint as the picker moves toward the magazine to cause the joint to break again as the picker swings in the reverse direction, thereby so to lengthen the picker stroke in the latter direction that the picker does not contact the transfer pad.

12. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, a spring normally holding the upper and lower elements of the knuckle joint in alignment, means controlled by the feeler, in the absence of an article at a detecting position, to rock the upper knuckle joint element out of alignment with the lower element as the picker is making its picking stroke, thereby abnormally to shorten said stroke, a movable control member which is in a normal inoperative position so long as the upper and lower elements of the knuckle joint are in alignment, but which is moved to an operative position when the upper knuckle joint element is rocked out of alignment with the lower element during the picking stroke of the picker, and a part carried by the upper knuckle joint which engages the control element, when the latter is in operative position, to rock the upper element of the knuckle joint out of alignment with the lower element as the picker approaches the transfer point.

13. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the

15

picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, arms projecting from opposite sides respectively of the upper element of the knuckle joint, a hook connected to one of said arms, said hook being so located as to be engaged by a feeler-actuated part, in the absence of an article from a detecting position, thereby to rock the upper element of the knuckle joint out of alignment with the lower element of the joint, a movable abutment for limiting movement of the other arm thereby to rock the upper element of the knuckle joint out of alignment with the lower element of the joint, and means for disposing said abutment in position to engage said latter arm in the absence of an article from the detecting position.

14. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, means controlled by the feeler to rock the upper knuckle joint element out of alignment with the lower element as the rod rises thereby to shorten the picking stroke of the picker in the absence of an article from a detecting position, an arm projecting from the upper knuckle joint element, and means cooperable with said arm in the absence of an article from the detecting position to rock the upper knuckle joint element out of alignment with the lower element as the rod moves down, thereby to augment the stroke of the picker in the label-delivering direction.

15. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating

16

rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, a hook pivotally connected to the upper knuckle joint element, 15 said hook being so located as to be engaged by a feeler-actuated member in the absence of an article from a detecting position during the picking stroke of the picker, thereby rocking the upper knuckle joint element out of alignment with the lower element, and a movable abutment which is so positioned relatively to the upper knuckle joint element, in response to said rocking of the latter by the hook, as to cause the upper knuckle joint element to rock out of alignment with the lower element as the picker moves in making its reverse stroke.

16. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, a hook pivotally connected to the upper knuckle joint element, 40 said hook being so located as to be engaged by a feeler-actuated member in the absence of an article from a detecting position during the picking stroke of the picker, thereby rocking the upper knuckle joint element out of alignment with the lower element, and a pivotally supported abutment which normally occupies an inoperative position, a part fixed to the upper element of the knuckle joint which engages the abutment, when the latter is in operative position, thereby to rock the upper element of the knuckle joint out of alignment with the lower element, and means for moving said abutment to the operative position when the upper knuckle joint element is rocked by the action of the hook.

17. In combination in a label-applying ma-

chine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, a hook pivotally suspended from the upper knuckle joint element, said hook being so located as to be engaged by a feeler-actuated member in the absence of an article from a detecting position during the picking stroke of the picker, thereby rocking the upper knuckle joint element out of alignment with the lower element, an elongate pivotally suspended control member, friction means operative to retain the control member in any position in which it may be placed, the control member having cam faces and an abutment, a lateral arm carried by the upper knuckle joint element, said arm having a part which is operative, as the picker makes its picking stroke by engagement with a cam face of the control member, to swing the latter from a normally inoperative position to an operative position whenever the upper knuckle joint element is rocked by the action of the hook, the abutment of the control member being so located, when the abutment is in operative position, as to limit movement of said lateral arm and thereby to rock the upper element of the knuckle joint out of alignment with the lower element as the picker approaches the transfer point.

18. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, a hook pivotally suspended from the upper knuckle joint element, said hook being so located as to be engaged by a feeler-actuated member in the absence of an article from a detecting position during the picking stroke of the picker, thereby rocking the upper knuckle joint element out of alignment with the lower element, an elongate pivotally suspended control member, friction means operative to retain the control member in any position in which it may be placed, the control member having cam faces and an abutment, a lateral arm carried by the upper knuckle joint element, said arm having a part which is operative, as the picker makes its picking stroke by engagement with a cam face of the control member, to swing the latter from a normally inoperative position to an operative position whenever the upper knuckle joint element is rocked by the action of the hook, the abutment of the control member being so located, when the abutment is in operative position, as to limit movement of said lateral arm and thereby to rock the upper element of the knuckle joint out of alignment with the lower element as the picker approaches the transfer point.

element, a hook pivotally suspended from the upper knuckle joint element, said hook being so located as to be engaged by a feeler-actuated member in the absence of an article from a detecting position during the picking stroke of the picker, thereby rocking the upper knuckle joint element out of alignment with the lower element, an elongate control member pivotally suspended from its upper end, means tending to hold the control member in any position to which it may be swung, the control member having inclined cam faces and having a hook near its lower end, a lateral arm carried by the upper knuckle joint element, said arm having a roll stud at its end which cooperates with the cam faces of the control member, the roll being engageable with one of said cam faces when the upper and lower elements of the knuckle joint are aligned as the picker-actuating rod rises, thereby to swing the control member to an inoperative position and being engageable with a cam face of the control member, when the upper and lower elements of the knuckle joint have been rocked out of alignment in response to the action of the hook, thereby to swing the control member to an operative position wherein the hook of the control member lies in the path of the roll, the parts being so arranged that engagement of the roll with the hook of the control member rocks the upper element of the knuckle joint out of alignment with the lower element as the picker reverses its direction of movement.

19. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, a control member which is moved from a normal inoperative position to an operative position if the knuckle joint is broken as the picker moves toward the magazine, and means engageable with the control member, when the latter is in operative position, to cause the knuckle joint to break again as the picker next swings in the reverse direction, thereby to lengthen the picker stroke in the latter direction so that the picker does not contact the transfer pad.

20. In combination in a label-applying machine of the kind which includes a magazine for labels, a two-element picker which swings in an arcuate path toward and from the magazine, a rock shaft on which the picker is mounted, a picker-actuating cam, means for transmitting motion from the cam to the rock shaft, said motion-transmitting means including a reciprocating rod and a knuckle joint comprising upper and lower elements, the lower element being fixed to the rod and moving up and down with the latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, the upper and lower elements of the knuckle joint being normally held in alignment by a spring, means for transmitting motion to the picker shaft from the upper knuckle joint element, a hook pivotally suspended from the upper knuckle joint element, said hook being so located as to be engaged by a feeler-actuated member in the absence of an article from a detecting position during the picking stroke of the picker, thereby rocking the upper knuckle joint element out of alignment with the lower element, an elongate control member pivotally suspended from its upper end, means tending to hold the control member in any position to which it may be swung, the control member having inclined cam faces and having a hook near its lower end, a lateral arm carried by the upper knuckle joint element, said arm having a roll stud at its end which cooperates with the cam faces of the control member, the roll being engageable with one of said cam faces when the upper and lower elements of the knuckle joint are aligned as the picker-actuating rod rises, thereby to swing the control member to an inoperative position and being engageable with a cam face of the control member, when the upper and lower elements of the knuckle joint have been rocked out of alignment in response to the action of the hook, thereby to swing the control member to an operative position wherein the hook of the control member lies in the path of the roll, the parts being so arranged that engagement of the roll with the hook of the control member rocks the upper element of the knuckle joint out of alignment with the lower element as the picker reverses its direction of movement.

latter, a device for applying adhesive to the picker as the latter approaches the magazine, means for holding an article to be labeled in the label-receiving position, a transfer pad which takes the label from the picker at a transfer point and applies it to the article, means operative to separate the picker elements to allow the transfer pad with the label to advance between the picker elements in approaching the article, a feeler which is responsive to the presence or absence of an article at a detecting position, a movable control member which is in a normal inoperative position so long as the knuckle joint remains unbroken, but which is moved from its normal position to an operative position if the knuckle joint is broken during the picking stroke of the picker, and means engageable with the control member, when the latter is in operative position, to cause the knuckle joint to be broken again as the picker next approaches the transfer point.

21. In combination in a label-applying machine wherein a label is applied to the article to be labeled by a label-holding pad, a rock arm for moving the pad toward and from the label-applying position, a pad carrier pivotally connected substantially midway between its opposite edges to said rock arm, the pivotal axes of the rock arm and pad carrier being parallel, a pad secured to the carrier, a spring tending to turn the pad carrier about its pivotal axis, and an adjustable stop operative to limit such movement.

22. In combination in a label-applying machine wherein a label is applied to the article to be labeled by a label-holding pad, a rock arm for moving the pad toward and from the label-applying position, a pad carrier pivotally connected midway between its opposite edges to said rock arm, the pivotal axes of the rock arm and pad carrier being parallel, a pad secured to the carrier, an adjustable stop operative to limit such movement, and abutment means operative to rock the pad carrier about its pivotal axis in opposition to the spring as the pad approaches the label-applying position.

23. In combination in a label-applying machine wherein a label is applied to the article to be labeled by a label-holding pad, a rock arm for moving the pad toward and from the label-applying position, a pad carrier pivotally connected midway between its opposite edges to said rock arm, the pivotal axes of the rock arm and pad carrier being parallel, a pad secured to the carrier, and means operative to position the pad carrier so that the label-contacting face of the pad is parallel to the label-receiving face of the article to be labeled as the label is pressed against the article by the pad.

24. In combination in a label-applying machine wherein an article to be labeled, having an upright face to receive the label, is supported upon a suitable support at the label-applying position, an applicator pad for applying the label to said upright face of the article, a rock arm mounted to turn about a horizontal axis, a pad carrier pivotally connected intermediate its upper and lower edges to the upper part of the rock arm so as to rock about a horizontal axis, a spring intermediate said arm and the carrier so arranged as to tend to rock the upper part of the carrier away from the arm, an adjustable stop for limiting such movement, a rigid arm projecting upwardly from the pad carrier, and adjustable abutment means, including a part carried by said arm, for positioning the pad carrier so that the label-contacting face of the pad is parallel to the label-receiving face of the article as the label is pressed against the article by the pad.

SIDNEY T. CARTER.
